(57) **CLAIM**

The ornamental design for a car center console storage box, as shown and described.

DESCRIPTION

FIG. 1 is a front perspective view of a car center console storage box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of car center console storage box in an alternate configuration.

The broken lines in the drawings illustrate the portions of the car center console storage box, which form no part of the claimed design.

1 Claim, 9 Drawing Sheets
